(57) **CLAIM**

We claim the ornamental design for a handheld tool, as shown and described.

DESCRIPTION

FIG. 1 is a front/right/top perspective view of the handheld tool;

FIG. 2 is a rear/left/bottom iso view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and

FIG. 8 is a rear elevational view thereof.

FIG. 9 is a rear/left/top view of the handheld tool in an optional partially extended configuration;

FIG. 10 is a rear/left/top view thereof in an optional fully extended configuration, with two tools also optionally extended; and,

FIG. 11 is a right side elevational view thereof in the optional fully extended configuration, with two tools also optionally extended.

The portions of the Figures shown in broken lines are not part of the claimed design and are for illustration only.
